UNITED STATES PATENT OFFICE.

HOWARD N. LITTLE AND WALTER B. GORMELY, OF LOCKPORT, NEW YORK.

AUTOMATIC LUBRICATING DEVICE FOR ROLLING MILLS.

1,425,110.

Specification of Letters Patent. Patented Aug. 8, 1922.

Application filed May 7, 1921. Serial No. 467,731.

To all whom it may concern:

Be it known that we, HOWARD N. LITTLE and WALTER B. GORMELY, citizens of the United States residing at Lockport, in the 5 county of Niagara and State of New York, have invented certain new and useful Improvements in Automatic Lubricating Devices for Rolling Mills, of which the following is a specification.

10 Our invention relates to improvements in automatic lubricating devices for rolling mills, more especially to means for lubricating opposite sides of sheet metal adapted to be passed through rolling mills for reducing the thickness of the sheet metal.

15 As now generally practiced, sheet metal, especially sheet copper in rolled form, is passed to and between the rolls of a rolling mill, and before entering the mill, the parts thereof are lubricated or oiled manually by means of an oil brush or swab passed back and forth by an operator standing at the side of the roll of metal. This results in portions of the metal receiving more oil 20 than other portions, and in some instances, the portions thereof passed between the rolls 25 of the mill without being oiled become scaled or other imperfections of the sheet metal are caused. This method of oiling 30 also results in a considerable waste of oil and is therefore expensive and at times ineffective, especially when thus oiled by an inexperienced or a careless operator.

The primary object of our invention is to 35 provide an automatic lubricating or oiling device in which oil is evenly fed, delivered, or transmitted onto both sides of the sheet metal, no more oil being used, when the device is properly adjusted, than is absolutely 40 necessary, with the result that a considerable saving of oil will result from the use of this invention over a period of time.

A further object of our invention is to 45 provide an oiling device in conjunction with a roll of sheet metal, so arranged that when the device is in action, it will be situated directly over the sheet metal at the point where it leaves the roll in a single strand or thickness; and in placing between 50 the single strand or thickness and the rolled portion of the metal, a distributer which rolls in contact with opposite sides of the sheet metal and which is so constructed that

oil delivered thereonto will thoroughly cover the exterior thereof, so that all portions of 55 opposite sides of the sheet metal will be thoroughly and evenly lubricated.

A still further object of our invention is to provide an oiling device which is movable so that it can be placed in position to 60 oil the distributer hereinbefore referred to, or so that it may be moved to one side in order that a new roll may be placed within the box-like structure in which the rolled material is placed and from which it is 65 drawn in a single strand or thickness to be fed to and between the rolls of the rolling mill.

With the above and other objects in view, 70 our invention consists in the novel features of construction and in the arrangement and combination of parts to be hereinafter described and more particularly pointed out in the subjoined claims.

In the drawings:—

Fig. 1 is a sectional elevation, showing 75 our improved device associated with a pair of guide rolls and the rolling rolls of a rolling machine.

Fig. 2 is an end elevation of the device.

Fig. 3 is an enlarged longitudinal section 80 taken on line 3—3, Fig. 2.

Fig. 4 is a vertical transverse section taken on line 4—4, Fig. 3.

Fig. 5 is an enlarged horizontal section 85 through a portion of the roll-receiving box taken on line 5—5, Fig. 2.

It is to be understood that our improved device may be used in connection with any form of rolling mill, and for this reason we have 90 not deemed it necessary to illustrate more than the two rolling rolls of a mill, between which rolls the metal is to be passed, and two guide rolls to guide the sheet metal, which guide rolls may, however, in many 95 cases be omitted, or other parts serving the same purpose substituted therefor.

Thin sheet metal material, and especially sheet copper or sheet brass is invariably kept in roll form, and when passing the same 100 through a rolling machine for reducing the thickness thereof, the roll of sheet metal is placed within a roll-receiving box or box-like retainer of the type shown in the drawings and designated by the numeral 6, said box-like retainer being supported on a suitable 105

frame-work 7, and in reality serving as a support for the rolled sheet metal. The sheet metal in roll form is gradually unrolled, and the portion unrolled is passed 5 upwardly out of the box-like retainer and passed between suitable guiding elements, such as shown by the guide rollers 8 in Fig. 1, from which it is continued rearwardly and directed through the pass provided be-
10 tween the two rolling rolls 9 forming part of any type of rolling machine.

As hereinbefore stated, the guiding device formed by the rolls 8 may at times be omitted, or other guiding means substituted 15 therefor. The rolling metal is so placed within the box-like retainer that it will uncoil from the side closest to the rear of said container or the side closest to the rolling machine, as at 10, Fig. 3, thus providing a 20 crotch or V-shaped space 11 between the rolled portion and that part of the unrolled portion adjacent said rolled portion, the unrolled portion of the sheet metal being shown at 12.

25 As far as known, the unrolling of the sheet-metal from the rear of the roll is a new departure and has not heretofore been used, as it has been the practice to unroll the metal from the front or forward portion of the roll, but in the use of our improved oiling device, the crotch or substantially V-shaped space 11 is utilized to good advantage, as will be explained hereinafter.

The bottom 13 of the box-like retainer 6 30 is slanted rearwardly, as shown, so that during the unrolling of the metal the tendency of the roll is to move rearwardly along the inclined bottom, thus assuring the formation of the crotch or V-shaped space between 40 the unrolled portion of the rolled portion of the metal at all times.

15 designates a support or upright fastened to one of the sides of the box-like retainer 6, as at 16, and secured thereto at a 45 suitable distance above the box-like retainer is a collar 17. 18 designates a combined oil-container and feeder, it being preferably formed rectangular and the container portion, designated by the numeral 19, has a 50 bottom 20, side walls 21, and end walls 22, said end walls being continued downwardly a distance below the bottom 20, as at 23. The portions 23 may be referred to as downward extensions of said end walls and 55 they are tapered toward their lower ends. Between the downward extensions 23 of said end walls an oil-trough 24 is arranged, said trough being V-shaped in cross section and divided into a number of chambers 25 60 by transverse walls or partitions 26. The lower end of the trough is provided with numerous small oil feeding openings 27, a series being provided for each chamber 25.

The combined oil retainer and feeder has 65 brackets 28 secured to one end wall thereof,

said brackets having openings therethrough and being passed over the support or upright 15, the lower bracket 28 bearing against the collar 17 secured on said bracket so as to pivotally hold said combined oil 70 container and feeder in elevated position, with the lower end of the oil-trough 24 a short distance above the level of the upper edges of the box-like container 6.

In the bottom wall 20 of the oil-container portion 19, pet cocks 29 or similar elements are secured in order to feed oil from said container portion into the trough 24 of the device, one pet cock being arranged over each chamber 25 of said trough.

In the drawings we have shown the oil container portion 19 equipped with five pet cocks and the trough 24 directly beneath with five oil chambers 25; and in Fig. 4 of the drawings, the two end pet cocks are 80 shown closed, while the three intermediate pet cocks are opened and feeding oil into the three intermediate chambers 25 of the trough; the feeding being arranged as described, due to the fact that the sheet metal to be oiled is approximately of a width 85 equaling the length of the three intermediate chambers 25 of said trough.

In the crotch or V-shaped space 11 formed between the rolled portion of the metal and the unrolled portion, we arranged a distributor in the form of a roll 30 which is 90 suitably constructed of a length of pipe 31 and a felt or other absorbent covering 32.

The box-like container 6 is provided with 100 movable supplemental side walls 33, opposite ends of which are fitted in grooves provided at the inner side of the rear and front walls of said box-like container by crimping a sheet of metal upon itself, as indicated at 105 34, the metal being so crimped that the grooves 35 are formed therein, the grooves at the front of the box-like container being aligned with those at the rear so that when a supplemental side wall is to be used, opposite ends thereof will be inserted in corresponding grooves 35 and thus retain said supplemental side wall parallel with the permanent side walls of said box-like container.

In Figs. 4 and 5 of the drawings we have shown two supplemental side walls 33 spaced equal distances from the permanent side walls so as to provide a space between the two supplemental side walls equaling, or approximately equaling the width of the sheet metal to be rolled. In this manner the sheet metal is drawn out by the rolls 9 of the rolling machine and its side edges retained at right angles to the axis of said rolls, or parallel with the permanent side walls of the retainer, thus preventing any distortion or irregularity when reducing the thickness of the sheet metal.

While we have shown the three interme- 130

diate chambers 25 of the oil-trough 24 feeding oil, it is apparent that with the width of metal shown in the drawings, the roll could be situated at one side of the box-like container 6, with one end thereof against one of the permanent side walls of said container, and a single supplemental side wall utilized and spaced from said permanent side walls a distance equaling the width of the metal. The sheet metal would then pass out of the box-like container 6 underneath the first three or the last three chambers 25 of the oil-trough 24, and consequently corresponding pet cocks would be open to feed oil into said three chambers, while the pet cocks above the two remaining chambers 25 would be closed.

In the drawings we have shown the pet cocks feeding oil from the container portion 19 into the three intermediate chambers 25 of the oil-trough 24 at a capacity to retain oil within said chambers at all times. The oil within said chambers drips through the drip openings 27 onto the distributor 30, the absorbent covering of which becomes thoroughly saturated by capillary attraction, and this covering distributes the oil onto one side of the sheet metal at the rolled portion thereof and to the other side thereof at the unrolled portion or single strand, the unrolling of the metal causing rotation of said distributor so that the oil is fed onto different portions of said distributor at all times, with the result that the absorbent covering thereof becomes thoroughly saturated and the surface moistened with oil to the same degree at all points thereof, thus assuring an even distribution of the oil onto the opposite sides of the sheet metal at all portions thereof.

In the event that the oil fed to the distributor is found to be excessive, the pet cocks over the feeding chambers 25 may be closed until all the oil within said chambers has dripped therefrom, after which the pet cocks may be opened to an extent to regulate the feed of oil into said chambers 25 to a degree that will prevent accumulation of oil therein yet permit the oil delivered thereinto to gradually drip through the opening 27 at the lower ends thereof, thus allowing surplus oil on the distributor or within the absorbent covering thereof to be consumed. It is of course to be understood that when the sheet metal to be rolled is of greater width than herein shown, it may be found necessary that four or even five chambers 25 of the oil-trough 24 must be utilized.

While we have shown five pet cocks and five chambers 25, it is apparent that the oil-trough 24 may be divided into a greater or a smaller number of chambers, and where the sheet metal rolled in a plant is always of the same width, the divisional walls or partitions 26 may be dispensed with or, if de-

sired, the entire trough 24 may be omitted and the oil fed onto the distributor 30 directly from the pet cocks.

When the sheet metal is fully unrolled and it is desired to place a new roll of metal 70 into the box-like container 6, the distributor 30 is removed from said container and the combined oil-retainer and feeder swung laterally, as indicated by dotted lines, Fig. 2, or to any position where it will not feed 75 oil into the box-like container, it being of course necessary to place a suitable receptacle upon the floor to catch the drippings from the oil-trough 24 when oil is contained therein.

While we have found the particular form of oil container and feeder shown and described herein to be highly efficient in feeding a limited or a regulated supply of oil to the distributor lying in contact with opposite sides of the sheet metal, we do not wish to be confined to the use of such a device, as any suitable oil feeding device capable of supplying oil to the distributor in desired quantities could be efficiently employed without departing from the principle of this invention.

Having thus described our invention, what we claim is:—

1. The combination with a rolling machine having a pair of rolling-rolls, of a support for a roll of sheet metal having a portion thereof unrolled and passing between said rolling-rolls, a distributor in contact with the rolled and the unrolled portions of 95 said metal, and means for feeding oil to said distributor.

2. The combination with a pair of rolling-rolls, of a support for a roll of sheet-metal having a portion thereof unrolled and leading to and passing between said rolling-rolls, said unrolled portion extending from the rolled portion of said roll of sheet metal to provide a space between the two, a cylindrical distributor situated in said space and 100 adapted to roll against opposite sides of the metal when being unrolled, and means for feeding oil onto said distributor.

3. The combination with a pair of rolling-rolls, of a box-like container, a roll of sheet-metal within said container having a portion unrolled and extending to and passing between said rolling-rolls, a supplemental wall within said box-like container, and means for retaining said supplemental wall in one 110 of a plurality of positions within said container.

4. The combination with a pair of rolling-rolls, of a box-like container having alined grooves at opposite walls, a supplemental 125 wall adapted to fit in any two alined grooves, and a roll of sheet-metal placed within said container and confined between said supplemental wall and a wall of said container parallel therewith, said sheet- 130

- 1 metal having a portion thereof unrolled and extending to and passing between said rolling-rolls, a rotatable distributer in contact with opposite sides of said sheet-metal, and 5 means for feeding oil to said distributer.
5. The combination with a pair of rolling-rolls, of a box-like container, a series of grooves at each of two opposite walls, the grooves of said walls being alined, a pair 10 of supplemental side walls adapted to have opposite ends thereof fitted in alined grooves, a roll of sheet-metal between said supplemental side walls having a portion thereof unrolled and extending to and passing 15 between said rolling-rolls, and an oil distributer in contact with said sheet-metal within said container.
6. The combination of an oil distributer acting against sheet-metal to be oiled, a V- 20 shaped elongated trough above said oil distributer divided into chambers, each chamber having drip openings at its lower end, and means for feeding oil into any number of said chambers.
25. 7. An oiling device for the purpose described, comprising an oil container and a plurality of pet cocks secured to the under side of said container, in combination with an oil-distributer onto which oil is delivered 30 from said pet cocks and whereby the oil is distributed onto sheet-metal.
8. An oiling device of the kind described, comprising an oil container having a plurality of controllable feeding elements and 35 a trough arranged underneath said container and divided into chambers corresponding in number to the number of said feeding elements, one chamber being underneath each feeding element and each chamber having a plurality of drip openings 40 therein.
9. The combination with a box-like container having an upright extending from one wall thereof, a combined oil-container 45 and feeder rotatably mounted on said upright, a roll of sheet-metal within said box-like container having a portion thereof unrolled and passing upwardly from said container, and a cylindrical distributer lying in 50 contact with both the unrolled portion and the rolled portion of said sheet-metal and adapted to receive the oil from said feeder.
10. The combination with a box-like con-
- tainer having a roll of sheet-metal therein with a portion of the metal unrolled and extending upwardly therefrom, an upright on 55 said box-like container, a combined oil-container and feeder pivotally supported on said upright and comprising an oil-container portion, a plurality of pet cocks secured in the bottom of said oil-container portion and an oil-trough beneath said pet cocks divided into chambers and having one chamber underneath each pet cock, each chamber having a plurality of feed openings at its lower end, and an oil-distributer comprising a metallic body and an absorbent covering for the same arranged underneath 60 said oil-trough.
11. The combination with a box-like container having a roll of sheet metal therein with a portion thereof unrolled and extending upwardly from the same, a cylindrical distributer having an absorbent surface and lying in contact with both the unrolled and 75 the rolled portion of said metal, and an oil-feeding device situated above said distributer and controllable to feed oil onto all or varied portions in the length of said distributor.
12. The combination with a rolling machine having a pair of rolling rolls, of a support for a roll of sheet metal having a portion thereof unrolled and passing between said rolling rolls, and a lubricating 80 roll simultaneously lubricating both sides of said sheet of metal.
13. The combination with a pair of rolling rolls, of a support for a roll of sheet metal having a portion thereof unrolled and 85 passing between said rolling rolls, an oil distributing device in contact with said sheet metal to oil the same, and an oil supplying device including means for supplying oil along selected lengths transversely. 90
14. The combination with a pair of rolling rolls, of a support for a roll of sheet metal having a portion thereof unrolled and 95 passing between said rolling rolls, and means for supplying oil along different transverse lengths to distribute oil according to the width of the sheet metal.

In testimony whereof we affix our signatures.

HOWARD N. LITTLE.
WALTER B. GORMELY.
